BEVERAGE BODY FOR TRUCKS

Eldon F. Miller, Leawood, Kans., assignor to Hesse Carriage Company, Kansas City, Mo., a corporation of Missouri

Filed Jan. 28, 1965, Ser. No. 83,611

Term of patent 14 years

(Cl. D14—3)

FIG. 1 is a perspective view of one side of the beverage body for trucks; and

FIG. 2 is a perspective view of the opposite side thereof.
The dominant features of my design reside in the portions shown in full lines.

I claim:

The ornamental design for a beverage body for trucks, as shown and described.
